WASHING APPARATUS FOR BOTTLE
WASHERS

Carl L. Trier, Baltimore, Md., and Jesse W. Fogg, Barrington, Ill., assignors to Cherry-Burrell Corporation, Wilmington, Del., a corporation

Original application May 6, 1937, Serial No. 141,084, now Patent No. 2,367,652, dated January 16, 1945. Divided and this application April 25, 1940, Serial No. 331,583.

5 Claims. (Cl. 134—48)

1

This invention relates to improvements in bottle washing machines and more particularly to improvements in the novel arrangement of mechanisms for washing the inside and outside of bottles by spraying washing solutions or water onto the same.

This application is a division of our copending application Serial No. 141,084, now Patent No. 2,367,652, dated January 16, 1945, entitled "Bottle washing machinery," which was filed May 6, 1937, and in which or divisions or which other novel features of our improvements in bottle washing machinery are fully disclosed and claimed.

In the construction of the conventional type of bottle washing machinery provisions are normally made for the pre-rinsing of bottles to be washed before they are passed or carried into the washing solutions on the interior of the washing machine. It is also conventional practice to wash the bottles after they have been soaked in a soaking solution by spraying washing solutions or cleansing water onto the inner and outer surfaces of the bottles. All such washing operations are normally carried out upon the bottles while they are suspended in carriers or supports in bottle conveying mechanism within the washing machine, which conveying mechanism usually moves by intermittent steps to thereby provide for the necessary time required for the various washing and rinsing operations which are performed during the dwell of the conveyor.

In the bottle washing machines of large capacities of the general type constituting the subject matter of this invention the bottle conveyors on the inside of the washer are usually of a width sufficient to accommodate a plurality of bottles arranged transversely of the conveyor. Such a conveyor usually consists of spaced chains provided with transversely extending frames containing bottle pockets.

Obviously in machines of large capacities efficiency and cost of operation become important items. Accordingly, it is desirable to include mechanisms in bottle washers which conserve the use of washing solutions, etc., which become especially wasteful when all of the washing and rinsing operations continue to operate even in the absence of bottles to be washed in the conveyor. The efficiency or effectiveness of the washing mechanism which spray water into and over the peripheries of the bottles also becomes an item of importance both as to the time required to satisfactorily wash a bottle and as to the quantity of water or washing solutions required to permit effective and efficient operation. Ac-

2

cordingly, the improvements in the efficiency of the washing mechanisms of bottle washers which normally depend substantially or to a great extent upon the manner of impingement of the streams or jets of water or washing solutions against the peripheries of the bottles becomes an element of importance.

The preferred embodiment of the invention in improvements in bottle washing machinery includes a bottle washer casing housing an intermittently movable bottle carrier or conveyor provided with bottle supports or pockets which are adapted to grip and maintain the bottle in relatively fixed position with respect to the bottle supports or pockets. The supports or pockets are also so constructed as to expose substantially all of the periphery of the bottle to the effect of the jets or sprays of washing water or solution while the bottles are being conveyed to the washing machine. The bottle washer is provided with one or more bottle spraying devices operable upon the bottle during periods of dwell of the conveyor, as well as bottle attempering means operable upon the bottles intermediate some of the washing operations to permit greater temperature variations and gradients between the temperatures of the various washing solutions or waters.

The prime object of this invention is to provide an improved bottle washer having novel pre-rinse mechanisms whereby the operation of the pre-rinse mechanisms takes place only when there are bottles to be rinsed present in the pockets at the pre-rinse station and whereby only that portion of the pre-rinse mechanisms which is associated with the pockets containing bottles is placed in operation.

The foregoing objects and other important features of the invention, which will become more apparent as the nature of the invention is better understood upon examination of the specification, drawings and claims, are preferably accomplished as illustrated in the preferred embodiment of the invention in bottle washing machinery in which are provided a plurality of improved and novel features involving the combination and arrangement of parts hereinafter more fully described.

The organization and method of operation will be best understood from the following description of the specific embodiments when read in connection with the accompanying drawings in which:

Figure 1 is a view showing the improved bottle washer largely in side elevation and partially in

65 section.

Figure 2 is an enlarged detail view showing the loading and discharge portions of the bottle conveyor in the improved bottle washer and the associated parts of the conveyor fragmentarily in side elevation.

Figure 3 is a fragmentary detail view in section taken along the line 3—3 of Figure 1.

Figure 4 is a fragmentary view taken along line 4—4 of Figure 2.

Figure 5 is a detail view in vertical transverse section taken along the line 5—5 of Figure 1.

Figure 6 is a detail view partially in plan and partially in horizontal section through the spraying device which is adapted to wash the bottles externally.

Figure 7 is a detail sectional view on an enlarged scale taken along the line 7—7 of Figure 6.

Figure 8 is a detail view in cross section of one of the preferred types of improved washing nozzles.

Figure 9 is a view similar to Figure 8 showing another preferred type of washing nozzle.

Figure 10 is a detail view in plan of the nozzle shown in Figure 8.

Referring to the figures, in which like numerals and identifying letters are used to identify like elements, 15 represents a frame-like support for a soaking tank 16 on which is erected a top portion 17 of the casing of the improved bottle washing machine.

At the opposite sides of the washer casing are provided generally symmetrically arranged upper guides or tracks 18 which may be made of angle-iron, as shown, for example, in Figure 5, to support the rollers 19 of the conveyor 20. The lower flight of the conveyor 20 is supported on similar symmetrically arranged guides or lower tracks 21, as indicated in Figure 1. The flight of the conveyor 20 in the lower portion of the bottle washing machine moves from left to right, as viewed in Figure 1, and the whole organization of the bottle washer represents novel improvements and arrangements in a more or less conventional type of bottle washing machine.

The improved bottle washing machine is adapted to receive soiled bottles at a loading station A in a substantially inverted position, as shown in Figures 1 and 2, to carry the bottles from the loading station A downwardly past a pre-rinse station B (Figures 1 and 2) through a soaking tank 16, as indicated at station C, and thence upwardly in a partially inverted position for draining the bottles, as shown at station D, to the washing station E, rinsing station F, sterilizing or chlorinating station G and thence to the unloading station H.

The nature of the intermittently movable chain conveyor generally indicated by the numeral 20, which conveys or carries the bottles 22 from one washing operation station to another through the improved bottle washer is best shown in Figures 2 to 5. There is a chain at each side of the washing machine and each chain comprises inner links and outer links spaced by rollers 19. These rollers turn upon pivot pins 23 which pivotally connect adjacent links in each of the chains.

Each of the inner links of the conveyor chains is formed to provide a bracket arm 24 projecting centrally or toward the opposite conveyor chain. The carrier frames 25 which bridge the space between the chains of the conveyor are mounted at their opposite ends upon the bracket arms 24, as clearly shown in Figure 5.

Each of the frames 25 is provided with bottle supports or gripping means or pockets 26 which

are arranged in a row extending transversely of each respective frame and which are adapted to engage and maintain bottles in substantially fixed position relative to the elements of the pockets 26 and the frames 25. By this procedure of maintaining the bottles in relatively fixed position the alignment of the bottles with the various washing mechanisms hereinafter to be described is facilitated. The pockets 26 are so constructed and operate in such a fashion as to contact and grip the bottles 22 only at spaced points about the outer periphery of the bead on the neck of the bottle.

The conveyor 20 is preferably given an intermittent or step-by-step movement, each step being equivalent to the distance from center to center of the consecutive carrier elements or frames 25. By locating the chain propelling means immediately adjacent the discharge station H it is possible to keep all slack out of the chains of the conveyor 20 throughout the upper flight of the conveyor which passes through that portion of the bottle washer in which a number of separate washing mechanisms which must register with the bottle are positioned. This arrangement assures an accurate registration of the several carrier frames and particularly the bottles 22 in the pockets 26 with the successive washing mechanisms positioned adjacent the beads of the bottles during each period of dwell of the conveyor 20 as the bottles are conveyed through the washing machine.

The preferred type of conveyor advancing mechanism includes levers 27 pivoted on a rock shaft 28 at opposite sides of the bottle washing machine. One of the levers 27 is provided with a slotted extension 29 which is engaged by a crank 30 which is mounted on a shaft 31. The levers 27 are each provided at their upper ends with dogs 32 adjustably limited as to their movement in one direction by adjustable stops or set screw means 33. The dogs 32 are, however, free to move pivotally in the opposite direction about fulcrum pins 34 whereby they are connected to and supported upon their respective levers 27.

Each of the dogs 32 is in the plane of the rollers 19. Upon the oscillation of the levers 27 in a clockwise direction, as viewed in Figures 1 and 2, the dogs 32 swing to the left and upwardly to ride over the rollers 19, dropping by gravity behind each of the rollers over which they pass. During the counter-clockwise oscillation of the levers 27, each of the dogs 32 will engage the rear portion of the adjacent roller 19 immediately ahead of it and will simultaneously engage its adjustable stop or screw 33, so that the rollers 19 will be propelled by the counter-clockwise movement of the arms or levers 27, thus advancing the entire conveyor 20 one step. The arrangement of the conveyor guides 18 and 21, as illustrated in Figure 1, is such that all of the slack in the chains of the conveyor 20 will occur at station I in the tank 16 where it cannot readily effect the registration of the bottles 22 in the pockets 26 with the several washing and attempering mechanisms positioned adjacent the path of travel of the bottles while they are being conveyed through the washing machine by the conveyor 20.

Between the conveyor feed station A and the station I, it is preferred to operate the pre-rinse jets with direct reference to the bottles themselves, thus eliminating any need for mechanical registration of the pre-rinse mechanism with the bottles in the pockets 26 of the conveyor 20 and thus also enabling the construction of a pre-rinse mechanism by which the operation thereof may

be prevented in the absence of bottles to actuate the mechanism.

The pre-rinse water supplied to the pre-rinse mechanism is supplied under pressure through pipe 35 best shown in Figures 2 and 4. This pressure may be derived either from the city water mains or from a pump 36 through connections 37, as shown in Figure 1. In any case the pipe 35 is provided with a series of orifices directed axially of the bottle openings or pockets 26 in the conveyor 20 and the bottles supported therein.

Each such orifice of the pipe 35 is individually connected or associated with a sleeve valve 38 which is provided with an aperture 39 registerable with the associated discharge orifice of the pipe 35. Obviously there are a series of sleeve valves 38 and the respective sleeve valves are in end-to-end engagement and are spaced from the end of the pipe 35 by the spacer tube 40.

Fastened to each sleeve valve 38 is at least one sleeve actuating lever 41 having its terminal portion 42 (Figure 2) in the path of the bead portion of the bottle carried in one of the pockets 26 which passes over the particular sleeve valve 38. It is broadly immaterial whether the sleeve valve 38 is rotatable step by step and provided with a number of levers 41 and a corresponding number of apertures or jets 39 or whether it is rotated in a port-opening direction by a bottle contacting a single lever 41 and is then rotated in the opposite direction by a weight or spring connected to the sleeve valve. As exemplifying the generic concept the simpler construction has been illustrated in which a single lever 41 and a single jet orifice 39 are provided on the valve 38 and in which the valve 38 is returned following each bottle-induced opening to its closed position by the effect of gravity on a counter-weight or by the effect of a closing spring, both of which are arrangements well within the scope of the knowledge of a mechanic.

At the end of each lever 41 in the preferred construction opposite the end of the lever which engages the bead of a bottle is a counter-weight which tends to oscillate each sleeve valve 38 individually to a position such that the jet orifice or port 39 of that particular valve will not register with the complementary orifice or aperture in the pipe 35. When a bottle encounters the terminus 42 of the lever 41 it will cause lever 41 to oscillate its respective sleeve 38 until the jet orifice 39 of that respective sleeve registers with the complementary orifice in the pipe 35 whereupon the pre-rinsing liquid under pressure in the pipe 35 will escape through the alining openings and will enter the mouth of the bottle to wash therefrom any extraneous or foreign matter which may readily be separable from the bottle.

A drain pan 44 catches the effluent from the rinsed bottle and is provided with a drain (not shown) for disposing thereof. This avoids undue pollution of the soaking solution in the soaking tank 16 of the bottle washing machine.

As soon as the bottle passes a position of alignment with the jet orifice in the sleeve valve 38 of the pre-rinse mechanisms the lever 41 of the respective sleeve valve so passed will be cleared by the bead of the bottle and will be closed by the weight 43 which causes the sleeve valve 38 to rotate into a closed position. If, as the various frames of the conveyor move past the pre-rinse station B, any of the bottle pockets in a frame 25 lacks a bottle the corresponding sleeve valve 38 will remain closed during the passage of the

empty bottle pocket past the pre-rinse station. This follows as a necessary consequence of the operation of the pre-rinse mechanism which requires the presence of a bottle in the bottle pocket before the lever 41 of the sleeve valve 38 can open the valve.

It will be noted from Figure 2 that the pre-rinse station B in the path of the conveyor 20 is not covered. Consequently the jets or streams of pre-rinse water from the valve 38 might, in the absence of a bottle in the pockets 26, spray out of the bottle washing machine if it were not for the individually operable sleeve valve arrangement whereby the valves depend absolutely upon the presence of a bottle in the bottle pocket for their operation.

After the bottle leaves the pre-rinse station B it is inverted to a right side up position and is immersed in and passed through a soaking solution in the soaking tank 16. Since the bottle will be right side up in this soaking tank and is immersed in the solution it will promptly fill with the hot soaking solution. As the bottle approaches the station D it will pass out of the soaking tank, be partially inverted and drained of its contents which will then return to the soaking tank, leaving the bottle empty.

The bottles, in passing from station D to the washing station E, are subjected to a cooling draft 30 of air which tends to temper the bottles and enable the use of soaking solutions and washing waters of greater temperature differentials than is possible in the conventional type of bottle washer. At station E the bottles carried in the frames 35 will in three successive advances stop in registration with washing mechanism which delivers jets of water from the pipes or headers 45 shown in dotted lines in Figure 1 which are operatively connected through suitable piping or conduits 40 with pump 36.

From the headers 45 in the preferred embodiment of the invention the wash water spraying into or impinged against the periphery of each of the bottles is supplied in two streams or jets. 45 These streams or jets are angularly divergent from each other and also pitched so that the streams of wash water will follow a helical path when they encounter the inner surface of a bottle. In Figures 8 to 10 are shown views of two 50 different types of jet nozzles effective for the purpose of impinging streams of water against the inner periphery of the bottle neck in such a manner as to cause the streams of water to follow a helical path upwardly along the inner surface 55 of the bottle registered with a nozzle.

The nozzle 46 shown in Figure 8 has an inner chamber 47 communicating with one of the headers 45. The jet orifices 48 of the nozzles communicate with the chamber 47 and are angularly divergent from each other, as shown in Figure 8, and are also inclined in opposite directions with reference to an axial plane at right angles to the section on which Figure 8 is taken. Consequently the jets of water discharged from the jet orifices 48 will be thrown into contact with or impinged against opposite sides of the interior of a superposed bottle and at the same time will be given a helical pitch such that the kinetic energy of the wash water discharged from the jet orifices will be sufficient to cause the water to travel helically up the inner surface of the bottle, thereby producing an effective scouring action upon that surface.

Much the same type of result is achieved by 75 the modified nozzle 49 which is shown clearly in

Figure 9. The jet orifices 50 thereof have the same position as the jet orifices shown in Figure 8 but, instead of being divergent upwardly, they are convergent upwardly. The pitch of the jet orifices 50 enables the jets of water exuding from these jet orifices to pass each other with ample clearance and to follow a helical path upwardly on the interior of the bottle surface upon contacting the same on opposite sides thereof. In both modifications of the improved nozzle the scouring effect of the whirling jets of water is substantially the same.

Over one row of these improved spray nozzles fastened onto and communicating with the interior of headers 45, the bottles 22 will also be washed externally by movable power sprays impinged against the outer surface of the bottles throughout the entire circumference and length thereof by means of a series of spray rings 51. These spray rings 51 are preferably connected integrally, as shown in Figure 6, thereby forming a part of the spray water supply pipe 52.

Figure 7 shows a section taken through a portion of the integrally formed spray rings 51 and spray pipe 52 at a point which is common to two adjacent spray rings 51 and consequently discloses spray orifices 65 and 66 opening from both sides thereof. These orifices are arranged at varying angles to the sides of the bottle so as to completely wash the same.

The two ends of the pipe 52 are mounted in carriage 53 provided with rollers 54 operating in guides 55. Each carriage 53 is connected by a pitman 56 with a lever 57 having a cam follower 58 engaged in the groove of a cam 59 mounted on the shaft 30, as shown in Figures 1 and 2.

The timing of the cam 59 and the motion of the lever 57 are such that, during each advance of the conveyor 20, the pipe 52 and its associated power or spray rings 51 will be elevated to a position shown in dotted lines in Figure 5 where they will clean the advancing bottles 22 carried by the bottle supports or pockets 26 of the conveyor 20. During each dwell of the conveyor 20 the cam 59 will cause the spray or power rings 51 to descend about the bottles 22 to the positions showing the pipe 52 in full lines in Figure 5. Throughout their advance and retraction the power rings 51 will, of course, be impinging jets or streams of water or washing solutions against all peripheral portions of the exterior of the bottles 22, thereby scouring them clean of soot or other extraneous accumulations.

The supply of water under pressure in the pipe 52 is provided by a flexible hose or tube 60 which connects pipe 52 to the outlet or discharge line leading from the pump 36. Before the next advance of the conveyor 20 the power rings 51 will again be elevated out of the path of the bottles 22 in the pockets 26 of the conveyor 20 which at that time are immediately below the power rings 51.

The water or washing solution discharged by the washing jets connected to the headers 45 and spray rings 51 supplied by the pump 36 is returned by a collecting or draining tray 61 to the sump 62 from which leads the intake of pump 36.

After the bottles have been thoroughly washed at station E by the various spray rings and nozzles, as just described, they are then advanced by the conveyor 20 to the rinsing station F from whence they pass, after being rinsed, to sterilizing station G at which station they are sterilized and then passed on to the discharge station H. At the discharge station H the bottles 22 which are

at that position supported in the conveyor in inverted order are automatically ejected from the pockets 26 of the conveyor 20 by tilting onto a tilting transfer table 63. The tilting transfer table completes the re-inverting operation by erecting the bottles and discharging them onto a discharge or cross conveyor 64 upon which the bottles are placed in upright position by the transfer table 63.

10 In the present invention an improved bottle washer has been provided which includes novel and efficient automatically operable washing and rinsing mechanisms provided with novel water spraying apparatus for effectively washing bottles in association with a soaking tank.

The prime individual advantage of the novel pre-rinse mechanism included in this invention resides in the simplicity of the construction and the efficiency of the operation thereof whereby the operation of each individual pre-rinse valve is limited to those instances in which bottles to be pre-rinsed are present in the portion of the conveyor which passes over the particular pre-rinse valve.

25 The improvements in the bottle washing machinery and arrangements of particular washing apparatus to effect the improved washing of the bottles, as hereinabove described, pertain primarily to the preferred embodiment of the invention. However, various modifications of the invention can readily be made by those skilled in the art. The invention is, therefore, not to be restricted except in so far as is necessitated by the prior art and the spirit of the appended claims.

30 The invention is hereby claimed as follows:

1. In a device of the character described, the combination with a bottle propelling conveyor having a bottle support adapted to grip a bottle and maintain it in securely fixed position relative to said support and a spray discharge means provided with a valve, a means in the path of a bottle propelled by said conveyor and connected with said valve and adapted to be actuated by 35 the bottle in a valve opening direction.

2. In a bottle washing machine, the combination with a conveyor having a bottle support adapted to maintain a bottle in securely fixed position relative to said support, of a trip device 40 in the path of a bottle in said support, a liquid spraying member having an orifice directed toward the position which such a bottle will occupy at one point in the movement of the conveyor, and a valve controlling discharge through said 45 orifice, said trip device being connected to said valve for the operation of said valve toward its open position, said trip device being so disposed that when the valve is opened by contact of said trip device with the bottle the bottle will be in a 50 position to receive a spray of liquid from said orifice.

3. In a bottle washing machine, the combination with a conveyor including a bottle carrier having a row of bottle receiving means, of a liquid 55 discharge tube extending transversely of the conveyor at a predetermined station thereof and provided with orifices spaced for registry with bottles supported by said means at said station, valves individually controlling the respective orifices, and means individual to the particular valves 60 extending into the path of bottle movement with said conveyor and positioned to be engaged by the individual bottles for opening the valves at the individual orifices when the bottles are at 65 said station.

4. In a bottle washing machine, a conveyor provided with a bottle support adapted to maintain a bottle in securely fixed position relative to said support, a spray discharge device provided with an orifice directed toward a supported bottle at a predetermined station along the path of said conveyor, means for actuating the conveyor, a valve controlling said orifice, and means for transmitting conveyor movement to said valve for the opening thereof, said means being disposed in the path of a bottle carried by said conveyor to transmit such movement only through said bottle.

5. In a bottle washing machine, the combination with a conveyor providing a series of carriers, each provided with a row of bottle supports, of a spray pipe extending transversely of the conveyor provided with orifices spaced to register with bottles in said supports at a predetermined conveyor station, sleeve valves rotatable upon said pipe and provided with valve openings registerable with said orifices, and means for rotating said sleeve valves individually, said means being disposed in the path of bottles carried by said supports for operation by said bottles in the course of conveyor movement to said station.
